(57) **CLAIM**

The ornamental design for a faucet filter, as shown and described.

DESCRIPTION

FIG. 1 is a Front elevational view of a faucet filter showing my new design;

FIG. 2 is a Rear elevational view thereof;

FIG. 3 is a Left side view thereof;

FIG. 4 is a Right side view thereof;

FIG. 5 is a Top plan view thereof;

FIG. 6 is a Bottom plan view thereof, and,

FIG. 7 is a Perspective view thereof.

The broken lines shown in FIGS. 5 and 7 inside the faucet filter represent portions of a faucet filter and forms no part of the claimed design. The area immediately outside of the broken line forms part of the claimed design.

1 Claim, 7 Drawing Sheets
